PRESSING MACHINE PAD COVER

Joseph J. Frank, Union, and Herman K. Rea,
Elizabeth, N. J.

Application June 22, 1949, Serial No. 100,656

7 Claims. (Cl. 38—66)

1

Our invention relates to pressing machines of the industrial type and more particularly to improvements in pressing machine pad covers.

In the usual commercial pressing machine a hollow buck is provided which has a plurality of passageways or apertures communicating with the interior of the buck to permit passage of steam and air into and out of the buck through the passageways. The top of the buck is provided with a plurality of pads usually of cotton or wool padding and a separate cover is arranged over these pads. The cover may be retained by springs or a combination of springs and rods and ropes or cords passing through a seamed fold around the cover when the edges and ends of the cover are tucked around the sides and ends of the buck. The steam and air pass through the pads and cover.

The usual pad cover and its retaining means are open to a number of real objections. Because of the uneven tension and pulling of the edges and ends of the pad covers over the pads and the edges and ends of the buck, wrinkles are introduced in the pad covers. These wrinkles reduce the working area of the pressing pad covers and cut production. In addition large steam losses are introduced due to the fact the creases provide natural passageways to release steam which comes up through the pads, this steam being directed in part toward the operator, causing discomfort. This also results in lowering steam pressure. Also, because of uneven tension produced by the conventional tensioning means, unstable surfaces are provided on the buck or pad due to the uneven pressure built up under the pad cover when some portions of the cover are more tightly pulled against the pad than other portions. These creases also result in creasing any silk or like cloth materials being pressed. This uneven tensioning of the cover also results in uneven drying when air is sucked through the pad into the buck. Furthermore, in the exposed ends of the usual spring elements catch on garments on the buck. The number of springs required for a passable retaining means in the usual arrangement are many. Also with the usual arrangement pads on the buck are also subject to sliding.

It is, therefore, an object of our invention to provide an improved pad cover for industrial type pressing machines which will eliminate the defects mentioned above.

A more specific object of our invention is to provide a novel pad cover which though employing springs for tensioning purposes provides even

2

tension along the sides and ends of the pressing cover, reducing the tendency to wrinkles and thus increasing pressing area and production.

Another object of our invention is to provide a pressing pad cover of improved design in which steam losses are reduced and the pressing surfaces are stabilized, thus reducing creases in silks and the like.

A further object of our invention is to so arrange the tensioning springs and cover that the exposed fastening hooks are eliminated, thus preventing catching on garments being pressed.

Another object of our invention is to provide a cover of the type described which will prevent sliding of pads.

A still further object of our invention is to provide a novel pad cover and tensioning device in which the tensioning is equalized throughout and in which the number of retaining springs is reduced to a minimum.

These and other objects will appear hereinafter.

The novel features which we believe to be characteristic of our invention are set forth with particularity in the appended claims, but the invention itself will best be understood by reference to the following description taken in connection with the accompanying drawing in which Figure 1 is an end view of one conventional type of industrial pressing machine, Figure 2 is a longitudinal section taken along the line 2—2 of the buck and pad shown in Figure 1, Figure 3 is a cross sectional view taken along the line 3—3 of Figure 2, Figure 4 is a layout of a cover made according to our invention, Figure 5 shows a detail of construction, Figure 6 shows the underside of the buck with a cover made according to our invention in use and Figure 7 shows a detail to explain a suggested theory of applicants' invention.

Referring to the drawings, in Figure 1 the usual industrial pressing machine is provided with a supporting frame 10 on which is mounted the buck 11 having the usual pressing element comprising the elongated hollow pressing member 12 having the chamber 20 and on which is mounted the padding 23 covered with the usual cover 22. The upper pressing element 13 is pivotally mounted at 14 and operated by means of the link mechanism 16 and foot lever 15. Steam can be directed to the hollow member 20 through conduits 18, the steam being controlled by a lever 19. As best shown in Figures 2 and 3, the hollow member 12 is provided with a plurality of equally spaced apertures 21 which permit steam to escape from the chamber 20 into and through pad-

ding 23 and cover 22. Springs 12' may hold the cover in place.

In Figure 4 we show a cover made according to our invention prior to its completion and positioning on the buck. This cover designated generally at 22 has the usual elongated shape and rounded ends, the ends being provided with the flaps 22' and 22'' which when sewed as shown in Figure 6 provide peripheral pockets for receiving the ends of the buck and also folds or channels which receive a draw cord shown generally at 36 in Figure 6.

In accordance with our invention the longitudinal edges of the cover have a series of truncated shaped portions 25 integral therewith. These portions are then folded so that the lines 28, 29 are in contact with each other and are then secured together by sewing along this line, the portion 30 being creased at 30' and being folded inwardly so that the portions between the crease 30 and the sewed together portions along lines 28, 29 form an inwardly extended tongue member 25', through which a rivet 31 is inserted through rivet holes 26, 27. Thus flaps are provided having upwardly extending portions with an inwardly directed tongue 25'. This inwardly directed tongue 25' is, folded against the portion 25 and when in use the rivet members are against the underside of the buck, the resulting flaps covering the rivet members as clearly disclosed in Figure 6. When the ends of the cover are fitted over the ends of the buck the draw string 36 is pulled tight and tied at 36' for example. Springs 35 provided with appropriate fastening hooks 35' are hooked into the eyelets or rivets 31' as indicated, the ends of the hooks being covered by the ends of the flaps. As a result of this construction the entire edges and ends are tightly pulled against the edge of the buck resulting in substantially eliminating all creases providing all of the resulting advantages pointed out above.

While the applicants do not wish to be limited to any theory, it is believed that perhaps the reason for the numerous advantages and results produced is due to the even distribution of the stresses and forces along the edges in the manner indicated in Figure 7. In a sense the stresses introduced by the spring through the flaps to the longitudinal edges may be looked upon as numerous single cords extending from the rivet 31 to the longitudinal edges of the cover which is pulled tight against the pads and pressing member. It is believed that stresses set up in the cover are as indicated in the diagram shown in Figure 7 so that all forces are evenly distributed from the edge to the point of pulling where the springs 35 engage rivets 31.

While applicants' explanation of what occurs may not be the correct one, actual covers built and tested do produce the results called for in the objects of the invention. Actual tests have indicated that as much as a fifty percent increase in production is produced by applicants' pad with a decrease in steam operating costs of over twenty percent since substantially all steam losses are eliminated. Elimination of creases in pressed garments, particularly of silk, result. Quick drying and stabilized pressing areas result with all of the advantages pointed out in the objects of applicants' invention. Snagging by the springs is eliminated, slipping reduced to a minimum and operator's comfort promoted.

While we have indicated the preferred embodiments of our invention of which we are now

aware and have also indicated only one specific application for which our invention may be employed, it will be apparent that our invention is by no means limited to the exact forms illustrated or the use indicated, but that many variations may be made in the particular structure used and the purpose for which it is employed without departing from the scope of our invention as set forth in the appended claims.

What we claim as new is:

1. An elongated pressing board cover having longitudinally extending edges, said cover having a plurality of flaps along its longitudinal edges, each of said flaps being creased normally of said edges to provide a fold having overlapped portions, said portions being secured together at their contacting edges remote from the crease, said fold extending inwardly of said flap to provide a tongue having means adapted to be secured to a tensioning device.

2. A pressing board cover having longitudinally extending edges and a peripheral pocket at each end for engaging the end of a pressing buck, said cover having a plurality of flaps along its longitudinal edges, each of said flaps having a fold comprising overlapped portions and providing a tongue, said portions being secured together at their contacting edges remote from the free edge of said tongue, said tongue extending inwardly of said flap and provided with an eyelet adapted to receive the end of a tensioning spring.

3. An elongated pressing pad cover having longitudinally extending edges and a peripheral pocket at each end for engaging the ends of a pressing buck, said cover having a plurality of flaps along its longitudinally extending edges, each of said flaps comprising a portion creased normally of said edges to provide a fold having overlapped portions, said overlapped portions being secured together at their contacting edges remote from said creased portion, said fold extending inwardly of said flap to provide a tongue and provided with an eyelet adapted to receive the end of a tensioning device.

4. An elongated pressing board cover having longitudinally extending edges, said cover having a plurality of triangularly shaped flaps along its longitudinally extending edges, each of said flaps having an inwardly extending tongue secured to said flap centrally thereof and along a line substantially normal to said edges, said tongue having means adapted to engage a tensioning means.

5. An elongated pressing board cover having a plurality of truncated-shaped flaps in opposed relationship spaced along the longitudinally extending edges, each of said flaps having a central portion folded to provide an inwardly directed triangularly shaped tongue, the folded portion being secured together along contacting portions remote from the free edge of said tongue whereby said truncated portions form triangularly shaped portions exclusive of said tongue, and eyelets secured to the tongues adjacent the base of the tongue near the point where said contacting portions are secured together.

6. An elongated pressing board cover having longitudinally extending edges and having a plurality of truncated shaped flaps in opposed relationship spaced along said longitudinally extending edges, each of said flaps being creased normally of said edges to provide contacting folded portions, said portions forming a triangularly shaped tongue extending from said flap,

said portions secured together along their contacting edges remote from the free edge of said tongue, said tongue extending inwardly of said flap and having means for engaging a tensioning device.

7. An elongated pressing board cover having longitudinally extending edges and peripheral pockets at the ends thereof, a plurality of truncated shaped flaps in opposed relationship spaced along said longitudinally extending edges, each of said flaps having a central portion folded along a crease to provide an inwardly directed triangularly shaped tongue, the folded portions on either side of said crease being secured together along their contacting edges remote from the free edge of said tongue, eyelets secured to the tongues adjacent the base of the tongue and where said folded portions are secured together, said peripheral pockets being adapted to

receive the ends of a pressing buck therein and, said tongues being adapted to contact the under surface of said buck, said eyelets being adapted to receive the ends of springs for tensioning said cloth evenly over said buck and along said longitudinally extending edges.
